UNITED STATES PATENT OFFICE.

NORBERT BRULÉ, OF ST. BARTHÉLEMI, QUEBEC, CANADA.

DESIGN FOR A DUSTPAN.

54,891.

Specification for Design.

Patented Apr. 20, 1920.

Application filed January 16, 1919. Serial No. 271,530. Term of patent 3½ years.

To all whom it may concern:

Be it known that I, NORBERT BRULÉ, a British subject, residing at St. Barthélemy, in the county of Berthier, Province of Quebec, Dominion of Canada, have invented a new, original, and ornamental Design for Dustpans, of which the following is a specification, reference being had to the accompanying drawing, forming part thereof.

The figure is a perspective view of a dustpan showing my new design.

I claim:

The ornamental design for a dustpan, as shown in the accompanying drawing.

Signed at St. Barthélemy, Quebec, Canada, this 17th day of May, 1918.

NORBERT BRULÉ.
